UNITED STATES PATENT OFFICE

2,206,951

TOWEL CABINET AND MECHANISM
THEREFOR

Albert C. Grunwald, River Forest, Ill., assignor
to Steiner Sales Company, Salt Lake City,
Utah, a corporation of Utah

Original application October 7, 1936, Serial No.
104,480. Divided and this application October
19, 1938, Serial No. 235,708

7 Claims. (Cl. 312—38)

This invention relates to improvements in sheet or web dispensing apparatus and provides devices which are applicable for handling either washable fabric material or paper or equivalent material.

5 The invention has been herein embodied in a mechanism for handling paper, the supply of which is in the form of a roll, from which lengths of sheets are fed and then torn off by hand.

This application is divisional of my co-pending 10 application Serial No. 104,480 filed Oct. 7, 1936, for Towel cabinet and mechanism therefor.

Objects are: to improve the automatic feeding means; to simplify the construction, and make it more compact; to dispose the time-stop and 15 automatic feeding mechanisms at one side only of the cabinet; and to balance the mechanism and make it more positive in action.

Features of the invention relate to the construction of the cabinet; the arrangement of two 20 doors to form a throat through which the paper is fed to be delivered to the user; the use of two doors swinging on a single pivot or on a common axis; the arrangement of the doors to swing 25 downwardly; the use of inner and outer members, one for the closure of a chamber of a supply roll, and the other for enclosing the first door and also for closing a portion of the cabinet not closed by the first door; the arrangement of a supply chamber below the dispensing mechanism with 30 a separate door for said chamber; the use of one of these members as a separate closure for the supply chamber, and the use of the other for giving independent access to the feeding mechanism; the use of a guard in relation to a measuring roll and to a closure-formed throat for 35 leading the paper from the measuring roll into said throat; the arrangement of the upper end of the inner or supply chamber closure, at a point near and under the measuring roll so that when 40 the door is closed the upper edge of this member is overhung by a portion of the measuring roll; the use of an element for guiding the paper into the door-formed throat; the use of a cutout in this guiding element so that the paper can be 45 observed and is accessible for adjustment after opening the outer door; and to all details of construction shown, along with the broader ideas of means inherent in the cabinet structure.

Another feature of the invention is the provision of three consecutive related chambers 50 spaced transversely of the cabinet and providing respectively a supply chamber, a chamber for a stop mechanism, and a chamber for a manually operable feeding mechanism, along with means

for separately closing the two last mentioned chambers, and with means for separately closing the supply chamber. Another feature is the co-operating of the separate closure means as a throat or paper-guiding means. 5

Objects, features and advantages of the invention will appear in the description of the drawings forming a part of this disclosure and in said drawings.

Figure 1 is a vertical section taken approximately on line 1—1 of Figure 2 looking in the direction of the arrow and showing the time-stop mechanism and related parts positioned as at the beginning of timing and before tear-off; 10

Figure 2 is a plan section taken approximately 15 on line 2—2 of Figure 1; and

Figure 3 is a vertical section taken approximately on line 3—3 of Figure 2.

Although my invention is herein embodied in a paper dispensing apparatus, there is no intention to entirely limit this invention to the dispensing of paper, since it may be applied in dispensing textile fabrics. 20

In the drawings, numeral 1 generally indicates a casing upon the bottom 2 on which rests a 25 supply roll of paper toweling indicated at 3. The casing has a closure member forming the front 4 of the cabinet and merging into a part 5 which forms the top of the cabinet. The part 4 is hinged at its bottom to the bottom 2 of the cabinet by means of a pintle 6 held in eyes suitably formed from the metal of the door and from the metal of the bottom 2. The top portion 5 of the closure, overlappingly engages a bead 7 of the rear wall 8 of the cabinet and a suitable lock 9 is provided 30 having a tumbler which engages in a slot (not shown) of the bead 7. 35

The lower part of the front portion 4 of the closure is cut out to provide a bottom-delivery opening 10 for the paper, and arranged adjacent this opening and mounted on the part 4 is a tear-off knife 11 having its tear-off toothed edge 12 arranged as shown to project slightly below the top of the opening 10. Cooperating with the portion 4 of the closure to form a guide throat is a plate 15 also hinged on the pintle 6. The inward movement of this plate is limited by lugs 16 of vertical partition plates 18—19 (see Figure 2). 40

The elements 4 and 15 form a downwardly leading guide throat 20. The lower part of the plate 15 curves outwardly and downwardly as indicated at 21 and is concave on its front side. The element 15 forms a closure for what may be considered the toweling supply chamber, and the back 45

50

of this chamber is provided with a diagonal stop or wall 22 which provides slight friction and prevents the roll moving against the back 8 of the cabinet.

- 5 Arranged above and inwardly from the top of the swing-plate 15, with its forward part close to and overlying the plate, is a measuring roll 25 having a shaft 26 or equivalent means suitably journaling it in and between the plates 18-19.
- 10 The plates extend from the front to the back of the cabinet and are secured by any suitable means preferably to the rear wall. The roll 25 has a suitable friction surface, and cooperating with this surface or with the paper lying there-
- 15 against is a pinch roll 27. The pinch roll has a shaft or trunnions 28 which project at opposite ends through slots 29 of the plates 18 and 19, and suitable spring means 30 is provided to act on the shafts 28 to yieldably move the roll 27 toward the
- 20 roll 25. A curved guard plate 31 partly surrounds and is spaced from the measuring roll as shown to form a guide for directing the paper around the roll, and downwardly into the throat 20 formed by elements 4 and 15. This guard and
- 25 guide plate has a cutout 31a giving access to the paper for adjustment thereof lengthwise of the roll.

The paper 32 is brought upwardly from the paper supply roll 3, then between the measuring 30 and pinch rolls 25, 27, then upwardly over the measuring roll, thence downwardly into the throat 20 formed by plates 4 and 15. The paper assumes the position best shown in Figures 1 and 2, and it will be seen that it is positioned to be 35 drawn against the teeth 12, and torn by an upward movement from side to side.

Referring to Figure 1 which shows the stop mechanism in stop position: attached to the shaft 26 of the measuring roll 25, is a spur gear 35 meshing with a second spur gear 36 on shaft 37 journaled in plate 18. Also on the shaft 26 immediately adjacent the gear 35 is a ratchet wheel 39, the teeth of which engage with the corresponding teeth of a ratchet bar 40, suitably guided 40 in part by means generally indicated at 41. A spring 42 is connected by one end to the top of the rack bar 40 and by the other end to bracket 43 of the plate 18. When the user pulls on the paper, the rack bar 40 is moved downwardly 45 against the action of the spring 42 by means of a roller 45 on the gear 36 acting against a spring arm 46, the outer free end of which cooperates with a slot 47 of the rack bar 40 and to move the rack bar downwardly against the action of the spring 42, to its lowermost position. The ratchet bar 40 has one face sliding against the gears and an opposite face sliding against the inner face of the guide 41. Thus the rack is kept in alinement so its teeth always properly co- 50 operate with the teeth of the ratchet wheel 39. Any suitable guide means can be used.

After the rack bar has reached its lowermost position, the spring arm 46 and the roller 45 have assumed the position shown in dot-and-dash 55 lines in Figure 1. The rack or ratchet bar has a shoulder 48 cooperative with shoulder 49 of latch 50 suitably pivoted at 51 to the plate 18. A spring 52 urges the latch 50 against a stop 53, to latching position, from which position it is 60 pushed by the curved lower end 55 of the rack bar 40, as this bar travels downwardly toward its final position of Figure 1. It is, of course, understood that the measuring drives gears 35 and 36 to cause the roller 45 to engage the spring arm 75 65 46 and force the ratchet bar to latched position.

During the motion of the ratchet bar from its uppermost position to its lowermost and latched position of Figure 1, a timing mechanism now to be described, is being set so that at the end of a time period it will trip the latch 50 and release 5 the back bar 40, which is then moved upwardly under the combined actions of the springs 42 and 46, to act through its ratchet teeth, upon the ratchet wheel 39, to rotate the measuring roll 25 and feed the paper outwardly to tear-off position. 10 It is noted that the timer (later described) has at this time been moved part way in setting direction.

The timer setting mechanism is generally of the type shown in co-pending application of Birr 15 Serial No. 15,271. This time-stop mechanism herein, comprises a stop arm 60 keyed to shaft 26 of the measuring roll, and a slide stop 61 suitably mounted, by means not shown, to freely slide vertically in the plate 18 across the path of arm 60. This slide stop 61 is connected by an arm 62 with a stem 63 of a plunger type air-displacing timer, generally indicated at 64. The outer end of the arm 62 acts as a trip, as will be later disclosed. The stem is urged downwardly by means of spring 65 connected by one end to an arm 66 of the stem and by the other end to a projection 67 of a bracket 68 which secures the timer barrel in operative position to the plate 18. The timer has an air vent 69, which operates 30 in a well known manner.

A link 70 is pivoted to the slide stop 61 as at 71 and has a slot through which a pin 74 loosely passes, which pin is threaded into the arm 60. The arm 62 forms a trip for the latch 50 and 35 engages a shoulder or stop 75 of the latch during its downward movement and retracts the latch against the action of its spring 52, thus releasing the ratchet bar 40 at the end of the time period. 40

To prevent the arm stop 60 from remaining in frictional contact with the slide stop 61, following its impact therewith, and therefore to prevent interference with a downward travel of the slide stop 61, a back-off mechanism is provided. The back-off mechanism is associated with the gear 36, and with the shaft 37 of this gear, which is a feature. Referring to Figure 3: On the inside of the plate 18 is arranged a disc 76 having a shoulder 77 which engages with a roller 78 carried by an arm 79 pivoted as at 80, and pressed by the spring 81 toward the disc 76. The back-off position of the parts of Figure 3 corresponds to the spaced relation of the end 80 of the arm 60, see Figure 1, relatively to the slide stop 61. Just before impact between arm 60 and slide 61 occurs the shoulder 77 engages the roll 78, and pushes the arm away from the disc 76 slightly. The spring then rotates the disc 76 in the opposite direction to back-off of the arm 60 and thus 50 brings its end 80 in the spaced relation shown in Figure 1. 55

Although in most instances there will be no need for manual means other than a pull on the paper to feed the paper or operate the measuring roll, I have thought it best to provide means, in addition to the automatic feeding of the paper after timing, by which the paper can be manually fed out if necessary. It may happen that when my invention is applied to a hand tear-off type of 65 cabinet, as disclosed herein, the user instead of grasping the small accessible portion of the towel and pulling it to the limit, will tear off this small portion. In such a case the automatic feeding means would not be set for operation 70 75 75

following the timing period of the time-stop mechanism.

I therefore provide the following manually operable feed-operating means: Referring now to Figures 2 and 3, on the end of the shaft 26 at the outer side of the plate 19, is keyed a ratchet wheel 90 having a pawl 91 to prevent reverse rotation. There is also provided a rack bar 92 having slots 93-94 with pins 95-96 passing respectively therethrough as shown. This rack bar projects through a slot in top of the casing so that it may be pressed downwardly by the finger, and the rack bar is normally held in its upper position by the spring 97, and out of contact with the ratchet wheel 90. The bar is guided by the slots and pins, and when pushed downwardly from the position shown in Figure 3, engages and drives the ratchet wheel 90 to move the measuring roll to project the paper sufficiently to be taken hold of. On release the rack bar again automatically assumes the position shown in Figure 3.

Operation

Assuming the rack 40 to be in its uppermost position and the timer stem in its lowermost position, and a portion of the paper to be accessible to the operator; the operator pulls downwardly on the paper rotating the measuring roll 30 in counterclockwise direction, and correspondingly rotating the gear 36 in clockwise direction, and moving the roller 45, to engage the spring 46 at a point near its support. As this motion continues the rack is brought to its lower or latched position, of Figure 1, and the link 70 raises the timer stem to the position shown in Figure 1. When this position is reached the stop arm 60 has engaged the slide stop plate 61, and the roller 45 has traveled in clockwise direction to the dot-and-dash line position, whereby its has flexed the spring arm 46, as shown, and this arm has acted to move the rack 40 to latched position. After the parts have been positioned as in Figure 1, the timer moves downwardly and until the projection 62 engages a shoulder 15 of the latch 50, and trips the latch. As soon as tripping occurs the rack 40 moves upwardly under the actions of the springs 42 and 46, the teeth of the rack cooperating with the teeth of the disc to rotate the measuring roll, and thus automatically feed the paper to accessible position.

The above construction gives a very positive feeding action at the end of the timing period, due to the combined actions of the springs and of course the spring tensions are so proportioned as to permit proper operation by relatively light pull on the paper, and without prematurely tearing the paper. Various grades of paper may be used, and a paper which is tough and at the same time absorbent is preferably used.

For loading the cabinet the door 4 is moved outwardly and downwardly to a position below the cabinet, and the door 15 is moved to a similar position. A supply roll is placed in the chamber with its back against the element 22 and with the paper coming upwardly from its bottom and from the front side of the roll. The paper is then passed upwardly between the pinch roll 27 and the measuring roll 25 and is brought around between the roll 25 and the guard 31. The roll 25 and the guard are so placed that the forward edge of the paper is guided upwardly then downwardly by the guard. The door 15 is then closed. The door 4 is then brought to a

horizontal position and the forward edge of the paper is threaded through the delivery opening, after which the door 4 is then closed, thus forming the downwardly leading feed throat. It is noted that the tear-off knife is arranged in opposition to the opening 10, the paper passing between the knife and the door 15, past the knife, thence outwardly through the opening.

Referring to Figure 1, it is seen that the door 15 closes only the central or supply chamber, and that the two laterally-formed chambers are closed only by the door 4. The mechanisms in the lateral chambers can therefore be inspected without opening the door to the supply chamber, and when the door 4 is opened the paper on the measuring roll can be seen, if the paper supply is not exhausted. Thus the cutout 31a serves as means for indicating whether or not there is need for a new supply.

I claim as my invention:

1. A paper dispensing cabinet having, an outer door and an inner door, each movable independently of the other and when in closed position together forming a throat, both doors being hinged on a common pintle, the outer door having a delivery orifice to which the throat leads, and a measuring roll within the cabinet mounted independently of said doors and from which the paper is led into said throat, thence through said delivery orifice.

2. A paper dispensing cabinet having an outer door and an inner door, each movable independently of the other, and when in closed position together forming a downwardly leading throat, both doors being hinged on a common pintle, the outer door having a delivery orifice to which the throat leads and which is near said pintle and bottom of said cabinet, a measuring roll within the cabinet mounted independently of said doors and from which measuring roll the paper is led into said throat, thence through said delivery orifice, said outer door having a tear-off knife with which the paper is in tear-off relation when projected through the orifice, said doors being adapted to swing downwardly to give access to the cabinet.

3. In a paper dispensing apparatus having a measuring roll, a presser roll below and cooperating with the measuring roll, a chamber below both rolls adapted to receive a supply roll and from which supply roll the leading edge of the paper is to be brought and introduced upwardly between said rolls, a member associated with the measuring roll to cooperate therewith to guide the leading edge of the paper after said edge has been passed between the rolls and cause the same to be directed upwardly and around the measuring roll and then forwardly toward the front of the cabinet, said cabinet having a delivery throat into which said member directs the leading edge of the paper after it leaves the measuring roll.

4. A paper dispensing cabinet having a door hinged to swing outwardly and downwardly, said door having a paper delivery orifice near the hinging point, a second door within the cabinet and spaced from the first door and also hinged to swing outwardly and downwardly and forming with the first door a throat leading to said delivery opening, both doors being hinged on a common pintle.

5. A dispensing cabinet having vertical partitions dividing it into a middle supply chamber and two lateral chambers, one at each side of the middle chamber, an inner door giving access

- only to the middle supply chamber, an outer door giving access only to the lateral chamber and said inner door, said doors being independently movable and together forming a delivery throat, a measuring roll defining the upper limit of the supply chamber, mechanism operable by the roll and arranged in one of the lateral chambers and viewable when said outer door is open, manual means for operating the measuring roll and arranged in the opposite lateral chamber and viewable when the outer door only is open.
6. A dispensing cabinet having vertical partitions dividing it into a middle supply chamber and two lateral chambers, one at each side of the middle chamber, an inner door giving access only to the middle supply chamber, an outer door giving access only to the lateral chambers and said inner door, said doors being independently movable and together forming a delivery throat,
- 5
- 10
- 15
- 20

the outer door having a delivery orifice to which the throat leads, a measuring roll defining the upper limit of the supply chamber, a stop mechanism for the measuring roll arranged in one of the lateral chambers and viewable when said outer door is open, and manual means for operating the measuring roll and arranged in the opposite lateral chamber and viewable when the outer door only is open.

7. In a paper dispensing cabinet having a dispensing roll, a plate extending longitudinally of and cooperating with said roll to guide the leading edge of the paper therearound, a presser roll cooperating with the dispensing roll, one end of said plate being near the presser roll, and an opening in the plate also near the presser roll for giving access for adjusting the paper lengthwise of the rolls.

ALBERT C. GRUNWALD. 20
